Des. 110,879

WALL CASE FOR A THERMOSTAT OR SIMILAR ARTICLE

Filed June 14, 1938

WILLIAM A. RAY,
INVENTOR;

BY

John H. Rouse

ATTORNEY

UNITED STATES PATENT OFFICE

110,879

DESIGN FOR A WALL CASE FOR A THERMO- STAT OR SIMILAR ARTICLE

William A. Ray, Glendale, Calif.

Application June 14, 1938, Serial No. 77,819

Term of patent 14 years

To all whom it may concern:

Be it known that I, William A. Ray, a citizen of the United States, residing at Glendale, in the county of Los Angeles and State of California, have invented a new, original, and ornamental Design for a Wall Case for a Thermostat or Similar Article, of which the following is a specification, reference being had to the accompanying drawing, forming part thereof.

The figure is a perspective view of a wall case for a thermostat, embodying my design.

I claim:

The ornamental design for a wall case for a thermostat or similar article, substantially as shown.

WILLIAM A. RAY.
